(57) **CLAIM**

The ornamental design for a cobra head lamp with small form factor electrodeless bulb, as shown and described.

DESCRIPTION

FIG. 1 is a bottom perspective view of the cobra head lamp with small form factor electrodeless bulb showing our new design;

FIG. 2 is a bottom plan view thereof;

FIG. 3 is a top plan view thereof;

FIG. 4 is a right side elevation view thereof;

FIG. 5 is a left side elevation view thereof;

FIG. 6 is an end elevation view thereof; and,

FIG. 7 is an opposite end elevation view thereof.

The broken lines shown on the drawings depict environment only and form no part of the claimed design.
